LASAGNA MACARONI

Stefano La Rosa, Woodhaven, N. Y., assignor to
V. La Rosa & Sons, Inc., Brooklyn, N. Y., a corporation of New York

Application March 5, 1952, Serial No. 18,782

Term of patent 14 years

(Cl. D8—1)

To all whom it may concern:

Be it known that I, Stefano La Rosa, a citizen of the United States, residing in Woodhaven, in the county of Queens, State of New York, have invented a new, original, and ornamental Design for Lasagna Macaroni, of which the following is a specification, reference being had to the accompanying drawing, forming part thereof, in which:

Figure 1 is a perspective view of a short cut of Lasagna macaroni, embodying my new design; and

I claim:

The ornamental design for Lasagna macaroni, substantially as shown.

STEFANO LA ROSA.
